FASTENING LACE

Robert Grabner, Bronx, N. Y.

Application September 30, 1932, Serial No. 635,500

15 Claims. (Cl. 24—117)

This invention concerns means facilitating the fastening of a taut cord and more particularly it concerns means by which such a cord is normally tied at a fixed length, such length being 5 however readily adjustable.

This invention will be hereinafter discussed and illustrated in connection with the tying of shoe laces. It may be readily applied to and adapted for other uses, such as gloves, garments or other 10 wear and closures, which are adjustably placed around objects of various sizes or for the purpose of a more or less tight fit.

One object of this invention is to provide means on a cord or string which may be readily moved 15 along the extent thereof, but which are fixedly located upon said cord or string when they are used to fasten it.

Another object of this invention is to provide 20 means for such fastening, hooking or tying, which are simple and durable in construction.

Another object of this invention is to provide 25 in connection with a hook or button fixedly disposed upon a garment and with strings by which said garment is laced, means adjustable upon said strings so that they may be arranged upon 30 said strings in a fixed preferred position, and so that they may be engaged upon said hook or button, holding said string in a taut position.

These and other objects of my invention will be 35 better understood from a variety of exemplary illustrations, which are described in the following, and which are shown in the copending drawing, in which:—

Fig. 1 shows a laced shoe to which my invention is applied.

Fig. 2 shows a detailed view of a ring, used in connection with the string of said shoe.

Fig. 3 shows a top view of a button over which said ring is hooked.

Fig. 4 shows a corresponding side view.

Figs. 5, 6 and 7 show side, top and sectioned end views respectively, of a modification of the ring of Fig. 2.

Fig. 8 illustrates a modification of my invention 45 in a sectioned rear view.

Figs. 9 and 10 show respectively a rear view and a cross-section of a disc used in connection with the modification of Fig. 8.

Fig. 11 shows another modification of the device which I adjustably arrange upon a string.

Fig. 12 shows the elevation of a hook preferably used in connection with the means of Fig. 11.

Fig. 13 shows the top view of another assembled modification of my invention.

Fig. 14 shows a cross-section of a bead used in the device of Fig. 13.

Figs. 15 and 16 show a top and a sectioned rear view of another modification of my invention.

Fig. 17 shows a detailed side view of the member engaged upon the string of the device shown in Figs. 15 and 16.

Figs. 18 and 19 show in side and end views, a modification, according to which the lock member may take the form of a plain bushing.

Figs. 20 and 21 show side and rear views of another form of the button, hook or binding post.

Similar numerals and letters refer to similar parts throughout the various views.

In Fig. 1 the lace L extends through the eye- 15 lets E of a shoe. Upon the lace L, at a certain distance away from the free ends F thereof, are fastened rings or members 21. Upon opposite sides of the shoe, a certain distance away from the lacing, are arranged buttons, posts or hooks 20 22 upon which the rings 21 are engaged, retaining the lacing in the tied position.

One manner in which the rings 21 may be 25 readily mounted upon the lacing L is illustrated in Fig. 2. The ring 21 is provided with substantially coaxial holes 23 upon opposite sides thereof, through which the lace extends to and away from the ring. Between the holes 23, the lace L is 30 slung once over the sides of the ring so that the center of the ring remains substantially free.

The lace L may readily be extended in the manner shown in Fig. 2 through the ring 21 and it is also understood how the ring may be readily 35 adjusted along the length of the lace. The lace L may or may not slide through the ring 21 when a particular tension is applied to its free end F, away from the ring.

But, when the ring 21 is hooked onto the binding post 22, the taut part of the lace L extending between the lacing and the ring pulls and engages the ring upon the inside 40 of the opposite side, from the outside of which extends the free end F, against the shank 24 of the button and the top of the shoe S, so that the lace, where it issues from the free end F through the 45 hole 23 into the ring 21, is squeezed or clamped against the said shank, and slippage of the lace L in the ring is prevented.

It is therefore understood that the ring is fixedly retained upon the string L, while it is engaged upon post 22 and 50 ties the shoe, whereas said ring may be shifted along the lace L when the ring 21 is unhooked from post 22.

A modification of the ring or member 21 is shown in the member 26 of Figs. 5, 6 and 7. 55

The member 26 may be compared with an angular frame which is slightly widened out at the centers 27 of opposite sides thereof, in order to allow the said member to be extended over a 5 button like the button shown in Figs. 1, 3 and 4. In a manner similar to that shown in connection with ring 21 in Fig. 2, the lace extends into and the free end F away from said member through suitable openings in the ends thereof. Near said 10 ends there are openings on one side of the frame or member 26, through which the lace L is slung onto the outside of the member 26, in between the holes through which it enters upon and issues from said member. These openings are 15 exemplarily indicated in the drawing by recesses 28 and 29 extending down from the top of member 26, so that the intermediary part 30 may be at random hooked over the side of member 26, extending through said recesses. The 20 profile of the frame or member 26 may be undercut between the top and bottom of the said member as indicated at 31, so that the lace L is retained substantially centrally between the top and bottom of said member, and so that the 25 lace is retained and compressed in a groove when the frame 26 is hooked over a post 22 and compresses the lace upon the inside of the frame, thus retaining the frame in a fixed position upon the lace.

30 In Fig. 8 I show a hook or binding post H extending from the shoe S. A disc 35 is pressed in abutment against the side of post H by the lace L, said lace extending through a hole 36 in the center and through two holes 37 and 38 laterally 35 removed on opposite sides from said center hole in disc 35. The manner in which the lace L extends through said disc 35 is illustrated in Figs. 9 and 10. Here we see the part 39 of lace L, which extends between the holes 37 and 38, extending 40 substantially across the center of the disc 35 where the lace L extends therefrom, so that the 45 said part 39 is pressingly engaged between the disc 35 and the post H after the lace L has been slung under the eye of hook H. It is therefore clear that the disc 35 is fixedly engaged by the 50 lace L when placed behind the post H whereas normally the lace may be adjusted through the various openings of the disc into a preferred position of the disc upon the lace.

55 In the modifications of Figs. 11 and 12, the bead 41 and the hook 42 take the place of the ring 21 and the button 22 of Figs. 1, 2, 3 and 4, respectively. A lug 43 extending from bead 41 fits into the eye 44 of hook or forked post 42. The lace 60 is extended through lug 43 near the base thereof, and then again through the bead so that it issues from said bead at a point diametrically opposite the lug 43. The part of the lace which extends through lug 43 is engaged and squeezed or 65 clamped by the hook 42, when the lace extending from the tied lacing is slipped under the hook 42, in the manner in which said lace was engaged upon the button or hook in the prior illustrations.

70 In Fig. 13 I show a hook similar to that of Fig. 12 but here a ball 46 takes the place of ring 21 of Figs. 1 and 2. Two substantially parallel holes 75 47 and 48 extend through the ball, and two of the respective entrances, 49 and 50, are arranged substantially diametrically opposite to each other on said ball. The lace is extended into opening 49, through hole 47, and the part 51 issuing from said hole is swung over into the other hole 48 past the point at which the lace L enters upon the ball 50 at 49 and the free end of the lace L extends from

the opening 50. It will be understood that the part 51 of the lace L is engaged and clamped by the hook 42 when the lace L is extended through the eye 44 of said hook. The free end F of lace L is of such length, that it may be freely manipulated in hooking the ball 46 behind the hook 42. 5

A groove 52 merging with the holes, may be extended around the ball and serves to keep part 51 in place; the part 51 partly protrudes from the groove above the surface of the ball, so as to 10 be engaged by the hook 42.

In the device illustrated in Figs. 15, 16 and 17, the member 55 and the hook 56 take the place of the ring 21 and button 22 of Figs. 1, 2, 3 and 4 respectively. The member 55 is folded over and 15 is preferably resilient. From one end of said member extends two short lugs 57 inwardly, there being sufficient space therebetween to allow the said lugs to retain the lace L between each other, at one end of member 55, whereas the free end of 20 lace L extends from member 55 through an opening 58 at the other end thereof. Normally the lace L may be adjusted longitudinally in member 55. But the member 55 clampedly engages upon the string or lace L and is fixedly retained 25 upon the latter when the lacing is tied by pulling the free ends F of the lace L, the lace is slung underneath the hook 56 and the taut lace L pulls the folded member 55 under the hook 56, so that the latter is engaged like a wedge upon the lace L. 30 The free end 60 of the hook 56 is struck down, so that it prevents the member 55 from sliding laterally out from thereunder.

The member bound on the lace L is just a bushing 61 in the arrangement of Figs. 18 and 19. 35 This bushing, upon which the lace L is engaged by being slung therearound, may be bound on any of the hooks or binding posts previously shown, or may be bound, like the other members previously shown on the post 63 of Figs. 20 and 21. 40 The lace L extends between the forks 64 which inclinedly arise from the shoe S, the member being locked behind said forks.

It is understood that the button, hook or binding post ordinarily is placed so far away from the 45 lacing, that the member does not have to be displaced along the lace, when the lacing is loosened up.

Having thus shown various modifications of my invention in detail, yet I do not wish to be 50 limited thereby, except as the state of the art and the appended claims may require, for it is obvious that other modifications and changes may be made in the form of embodiment of my invention, without departing from the spirit and 55 scope thereof.

What I claim is:—

1. In combination with a binding post for tying a lace, a perforated member, said lace substantially fitting one perforation in said member, 60 and said lace shiftably extending through said one perforation and over said member so that it is wedged between said member and post, when said member is engaged on said post under the tension of the lace extending from said member. 65

2. In combination with a binding post for tying a lace, a perforated member, said lace substantially fitting one perforation in said member, and said lace being looped through said one perforation and over said member so that it is wedged 70 between said member and post, when said member is engaged on said post under the tension of the lace extending from said member.

3. In combination with a binding post for tying a lace, a perforated member to and from which 75

extends said lace, said lace substantially fitting one perforation in said member, and convolutions in said lace loosely engaged upon said member but bound thereon by said post when said member is engaged on said post under the tension of said lace.

4. In combination with a binding post for tying a lace, a perforated member, said lace substantially fitting one perforation in said member, 10 said lace shiftably extending through and over said member, but being disposed between said member and said post and fixedly fastened on said member when said member is hooked onto said post.

15 5. In combination with a binding post for tying a lace, a perforated member to and from which extends said lace, said lace substantially fitting one perforation in said member, and convolutions in said lace engaged upon said member, and 20 volutedly fixedly between said member and said post and fastened on said member when said member is hooked onto said post.

25 6. In combination with a binding post for tying a lace, a perforated member, said lace being looped through a plurality of perforations in said member, said lace substantially fitting one perforation in said member and being engaged between said member and said post, when said member is hooked onto said post against the 30 tension of said lace.

35 7. In combination with a binding post for tying a lace, a perforated member, said lace being looped through a plurality of perforations in and over said member, said lace substantially fitting one perforation in said member and being guided thereby so that it is wedged between said member and said post when said member is hooked onto said post.

40 8. In combination with a binding post, a round member engageable on said post, perforations extending through said member, and a lace substantially fitting one perforation in said member and adjustably looped through said perforations but bound therein when engaged between the 45 assembled member and post.

9. In combination with a binding post, a round member engageable on said post, perforations extending through said member, and a lace substantially fitting one perforation in said member and looped through said perforations and over a round part of said member, said round part of the member facing the post when assembled therewith.

10. In combination with a binding post, a member, perforations extending through said member, and a lace substantially fitting one perforation in said member and looped through said perforations and over said member where said member faces said post when engaged thereupon.

11. In combination with a binding post, a round 15 member engageable in said post, relatively angular perforations extending through said member, and a lace substantially fitting one perforation in said member and looped through all of said 20 perforations.

12. In combination with a binding post, a round member engageable on said post, perforations extending through said member, a lace substantially fitting one perforation in said member and looped through said perforations, and 25 a groove in the surface of said member accommodating said lace.

13. In combination with a binding post, a round member engageable on said post, perforations extending through said member, a lace 30 substantially fitting one perforation in said member and looped through said perforations, and a groove in the surface of said member accommodating said lace and connecting a pair of said 35 perforations.

14. In combination with a binding post, a perforated ring fitting over said binding post, and a lace substantially fitting and extending through perforations in said ring.

15. In combination with a binding post, a per- 40 forated ring fitting over said binding post, and a lace substantially fitting and extending through perforations in and slung over said ring.

ROBERT GRABNER.
